UNITED STATES PATENT OFFICE

OTTO EINSLER, OF LEVERKUSEN, GERMANY

ARRANGEMENT FOR REGULATING THE DISCHARGE OF THE HOT GASES IN STEAM-BOILER FIRINGS

Application filed February 19, 1930, Serial No. 429,782, and in Germany January 25, 1928.

It is usual with steam boiler firings to build adjustable shut off elements in the hot gas flue leading from the end of the boiler directly to the main flue, in order to divert the hot gases as required to heat exchanging elements for preheating air, feed water or the like.

This is open to the objection that flap registers are generally used as shut off elements, the packing surfaces or edges of which elements do not close tightly, owing to warping and wear in service, so that a portion of the hot gases still available for preheating, unintentionally escapes through the registers without being utilized in the heat exchangers, thereby reducing the heat efficiency degree of the firing plant.

This invention obviates this objection in that a bell—or similarly shaped closing element, known per se, is used as a shut off element and consists of a solid bell, plate, disc or the like, the packing edge or surface of which sits like a valve on its seat surface and ensures an absolutely tight closure, which may be made yielding by a packing material, such as asbestos, sand or the like, arranged in a cavity of the seat surface. The bell is actuated in a suitable manner similarly to the usual registers by chains, rods, shafts or the like, which are suitably protected against the action of the hot gases.

An embodiment of the invention is illustrated by way of example in the accompanying drawing, the only figure of which shows diagrammatically such an arrangement in a steam boiler plant.

In the extreme flue 1 for the hot gases, which leads the waste gases from the fire box directly to the main flue 2 as illustrated by an arrow in full lines, a bell closure 3 is fitted as shut off element, the edge of which bell rests on a seating surface 4 of channel like cross section owing to its upwardly directed flanges 5 and made yielding by a filling of sand. The bell 3 is reinforced by bows 6 and guided by means of a rod 8 in a transverse bar 7 so that it can be raised and lowered by means of a chain 9. When the bell is in raised position, the waste gases

pass directly into the main flue, whereas, when the bell is lowered, they are diverted in a manner known per se as illustrated by an arrow in broken lines from the fire box, to the heating elements of which the lower drum 10 of the feed water preheater is shown in the drawing.

In hot gas flues of larger diameter a number of small juxtaposed bells may be provided instead of a correspondingly large bell closure. The bell need not be circular, but may be adapted to the cross section shape of the hot gas flue.

I claim:

Means for regulating the discharge of hot gases in a steam boiler firing wherein the firing includes a hot gas flue and a main flue, comprising a shut-off element in the form of a bell closure disposed between the hot gas and main flues.

In testimony whereof I affix my signature.

OTTO EINSLER.
